(57) **CLAIM**

The ornamental design for a capacitive sensor, as shown and described.

DESCRIPTION

FIG. 1. is a perspective view of the front, right, and top sides of a capacitive sensor showing our new design;

FIG. 2. is a front view thereof;

FIG. 3. is a rear view thereof;

FIG. 4. is a right side view thereof, a left side view being a mirror image thereof;

FIG. 5. is a top plan view thereof; and,

FIG. 6. is a bottom plan view thereof.

The broken lines shown represent portions of the capacitive sensor and form no part of the claimed design.

The dash-dot lines represent the boundary between the claimed design and unclaimed design and form no part of the claimed design.
